UNITED STATES PATENT OFFICE

151,238

DESIGN FOR A PARING KNIFE

Leo A. Heintzelman, Grand Rapids, Mich.

Application October 25, 1946, Serial No. 134,224

Term of patent 3½ years

(Cl. D22—3)

To all whom it may concern:

Be it known that I, Leo A. Heintzelman, a citizen of the United States, residing at Grand Rapids, in the county of Kent and State of Michigan, have invented a new, original, and ornamental Design for a Paring Knife, of which the following is a specification, reference being had to the accompanying drawing, forming a part thereof.

Figure 1 is a perspective view of a paring knife, showing my new design.

Figure 2 is an exploded view of the same in side elevation.

I claim:

The ornamental design for a paring knife, as shown.

LEO A. HEINTZELMAN.
